UNITED STATES PATENT OFFICE.

GEORGE A. LITCHFIELD, OF SOUTHERIDGE, MASSACHUSETTS. ASSIGNOR TO LITCHFIELD SHUTTLE COMPANY, OF SOUTHERIDGE, MASSACHUSETTS, A CORPORATION OF MASSACHUSETTS.

SELF-THREADING LOOM SHUTTLE.

Application filed October 12, 1927. Serial No. 225,770.

This invention relates to loom shuttles, and particularly to those of the self-threading type in which the thread or yarn is required to automatically thread itself after a fresh 5 bobbin has been inserted in the bobbin chamber of the shuttle.

The present improvements are intended to provide a construction that will, to the greatest possible degree, facilitate the easy and 10 certain threading of the shuttle, while reliably preventing the accidental escape of the yarn therefrom after it has been threaded.

In the efforts to produce a threading construction that will be proof against unthreading, the practical tendency has been 15 toward providing means for overhanging the thread passage, such means being usually so arranged as to obstruct or impede the usual threading of the shuttle. My present improvement is designed to provide threading 20 means which will, to the greatest possible degree, facilitate passage of the thread into the yarn-admitting passage without obstruction, while providing an adjacent thread passage 25 so arranged that the yarn must pass from the admission slot into the thread passage, while making it virtually impossible for the 30 yarn to escape from the thread passage into the admission passage or slot. Furthermore, means are provided, intermediate of the 35 forward and rear ends of the passage, to choke or restrict the ballooning of the yarn both for the purpose of providing any desired tensioning of the yarn and also to prevent the ballooning from carrying it out of the thread 40 passage, and thus lead to possible de-threading of the yarn. One advantage of the present improvement is that it is exceedingly simple and inexpensive to construct in exactly 45 the form and proportions desired, and avoids the troublesome practice in vogue heretofore of attempting to cast the thread-block in an open or distorted shape and thereafter bend the parts of the thread-block into their desired final position or relationship after it has been machined.

In the accompanying drawings I have illustrated a form of construction and arrangement embodying the principles of this invention, in which:

Figure 1 is a plan view of the forepart of a shuttle containing my improved threading block properly secured therein.

Figure 2 is a cross sectional view on the plane 2—2 of Figure 1. 55

Figure 3 is a detail plan view of the threaded block detached from the shuttle.

Figure 4 is a rear end elevation of the same.

Figure 5 is a side elevation of the threader block as viewed from the outlet side of the 60 shuttle.

Figure 6 is a bottom plan view of the threader block.

Figure 7 is a front elevation of the threader block. 65

Figure 8 is a detail view in rear elevation of the threader block-casting before it is machined in the manner hereinafter described.

In practice, the shuttle body *a* has the usual 70 forepart *b*, provided with the threader block containing recess *c* in which the threading block is firmly secured by the usual locking bolt 10 passing transversely through its rearward bottom portion. As usual also, the block-receiving recess is provided with a lateral outlet passage *d* for permitting the delivery of the yarn in the weaving operation. 75

The threader block 1 comprises a rear portion occupying about one-half the length of the block that is wide enough to extend substantially beyond the medial axis of the shuttle on both sides, and is partly subdivided by a longitudinal vertical slot located to form the main deflecting member 3 and the supplemental deflecting member 4, the former having a forwardly projecting continuation of conoidal form forming a deflecting beak 2, terminating in a downwardly extending tapered tip 2^a, lying adjacent to the opposite vertical wall of the forward portion *c'* of the recess *c*, the beak overhanging the outlet passage *d* into which the inthreading yarn is deflected by the downwardly and rearwardly inclined surface of a deflecting horn 5, arranged at the forward end of the threader 85 block. 90

As clearly shown in Figures 2, 4 and 7, the top surface of the rear half of the threader-block casting is formed with oppositely inclined or curved, downwardly extending sur- 100

- faces forming a sort of elongated converging throat through the rear half of the threading block. This converging throat or trough can be readily slotted longitudinally to any desired width, according to the size of the yarn that the shuttle is intended to use, this forming a vertical admission or inlet passage without the slightest obstruction to the admission of the yarn to the bottom thereof.
- 10 The main rear portion 3 is longitudinally bored or drilled to any desired diameter, according to the range of yarn to be used, as shown at 3^a, this bore extending in substantial parallelism with the admission slot 1^a, through the rear half of the thread block, and being divided or separated from the admission passage by the depending lip portion 3^b of the main rear member 3. By means of a broach the lower portion of this vertical separating wall 3^b can be cut away to form a narrow longitudinal communicating slit for the passage of the yarn from the bottom portion of the admission slot into the yarn-confining passage 3^a. These operations are readily performed so as to give each slot or passage the desired width or diameter to suit the particular requirements of the various sizes of yarn, whether cotton, silk or wool, for which the shuttle is intended.
- 20 It will be noticed that the forwardly extending inner edge of the conoidal beak 2 is laterally offset with relation to the admission slot 1^a, and its inwardly sloped surface at this point forms a continuation of the similarly sloped surface of the rear member 3 to insure the deflection of the yarn into the bottom of the slot 1^a. It will also be noticed that the longitudinal slot 1^a, and the inner edge 2^b of the beak, while arranged in laterally offset planes, are disposed in planes slightly oblique to the longitudinal medial axis of the shuttle so that if these two planes be continued they will intersect different portions of the side wall c² of the forepart recess through which the yarn passes in the inthreading operation. The downwardly extending tapered tip 2^b is located in close proximity to the opposing portion of the wall c², the intervening space here being preferably very slightly narrower than the diameter of the yarn to be used but not sufficiently narrow to prevent easy passage of the yarn under and around this tip as it is deflected downwardly by the forward edge of the deflecting horn 5.
- 30 In line with the undercut portion 5^a of the forward horn 5 is mounted the usual wear pin 6, which may be of hardened steel or porcelain, around which the yarn makes a quarter turn as it passes through the lateral outlet passage d.
- 40 A felt plug 7 is inserted in the thread-block so as to pass through the yarn passage 3^a, intermediate of the ends thereof, and to avoid obstructing the communicating slit forming the entrance to the thread passage 3^a, this intermediate plug is set obliquely in the threader block, thus confining the ballooning to the upper portion of the yarn passage. This arrangement of the yarn-retarding and choking member 7 permits the sufficient freedom of the yarn uncoiling over the end of the bobbin, while it makes it virtually impossible for the yarn to accidentally escape from the yarn passage since its revolution, while unwinding, is in a direction that guides it away from any tendency to pass out through the communicating slit and, furthermore, owing to the considerable length or elongation of the partition wall 3^b, there is not the opportunity for a loop of the yarn to pass out of this elongated slot, such as is afforded when only a narrow or short obstruction is provided against the escape of the yarn.
- 50 The main deflecting surface for inverting the yarn into the shuttle, of course, is formed by the inwardly sloped surface extending from the rear of the member 3 to the forward point or end of the beak, while the opposing rear member 4 does provide an inward and downward deflecting surface when the ballooning yarn impinges upon that side of the admission slot. The member 4 also forms a brace for receiving and supporting the inward thrust of the pressure exerted by the spring-pressed shuttle box arm against the cut away and weakened forepart wall on the inlet side of the shuttle, and this prevents the splitting of this wall which often results from such pressure. The member 4 is provided with a lateral boss 4^a seated in a suitably formed socket or vertical recess to aid in holding the shuttle threader in precisely the correct position, and this anchoring is further supplemented by a depending lug 8 seated in a corresponding recess in the bottom of the portion of the forepart. The forward end or apex of the conoidal beak 2, instead of being depressed or bent downwardly, lies in an elevated plane a substantial distance above the bottom of the deflecting horn so that there is no tendency to prevent the yarn from readily slipping around the depending tip of the beak into deflecting engagement with the forward inclined edge of the horn 5. Indeed the yarn has the utmost freedom of ingress for the inthreading movement, while, owing to the construction and relation of the parts described, accidental escape from its proper threaded position is practically impossible under actual conditions of service.
- 60 What I claim is:
1. A self-threading shuttle embracing in its construction a shuttle fore-part formed with a block-receiving recess, a threading block secured therein, the rear half of said block being provided with a thread-admitting slot between vertical parallel walls whose upper surfaces are oppositely inclined

- throughout their length to lead the thread into the bottom of said slot, the portion on the inlet side of said slot being longitudinally bored to form a longitudinal thread passage 5 substantially parallel with said slot, the intervening depending wall being cut away slightly above the level of the bottom of said slot to form an elongated slit for the admission of the thread from said slot into 10 said thread passage, the upper portion of the block, forwardly of said slot, forming a deflecting conoidal beak terminating in a downward projecting tip in proximity to the opposite side wall of the thread block recess. 15 2. A threading block for insertion in the block-receiving recess of a shuttle forepart, embracing in its construction a longitudinal block whose rear portion is substantially offset beyond the inner edge of its forward portion 20 and is provided with an elongated vertical longitudinal admission slot forming a downward continuation of convergent top surfaces on opposite sides of the slot beyond the medial axis of the shuttle from the outlet side, the block being also provided with a longitudinally bored thread passage extending alongside the vertical slot on the outlet side thereof and having communication with said slot through an elongated narrow slit 25 located at the bottom of the slot, the forward portion of the block forming a conoidal beak, and having an underneath horn whose forward edge is inclined rearwardly and downwardly to guide the yarn downwardly and rearwardly into the thread-eye of the shuttle. 30 3. A thread block for insertion into a receiving recess in the forepart of a shuttle, embracing a conoidal surfaced forwardly extending beak whose approximately straight inner edge extends slightly beyond the medial axis of the shuttle and a rearward portion laterally offset beyond the inner edge of the beak, said offset portion extending approximately half the length of the block 35 and being vertically slotted throughout its length and having downwardly sloped convergent top surfaces leading into said slot, a longitudinally disposed yarn passage extending alongside said slot and separated 40 therefrom except at the bottom by a vertically depending elongated partition wall arranged to prevent the lateral escape of yarn from said passage. 45 4. A thread block for insertion into a receiving recess in the forepart of a shuttle, embracing a conoidal surfaced forwardly extending beak whose approximately straight inner edge extends slightly beyond the medial axis of the shuttle and a rearward portion laterally offset beyond the inner edge of the beak, said offset portion extending approximately half the length of the block 50 and being vertically slotted throughout its length and having downwardly sloped convergent top surfaces leading into said slot, 55 ceiving recess in the forepart of a shuttle, embracing a conoidal surfaced forwardly extending beak whose approximately straight inner edge extends slightly beyond the medial axis of the shuttle and a rearward portion laterally offset beyond the inner edge of the beak, said offset portion extending approximately half the length of the block 60 and being vertically slotted throughout its length and having downwardly sloped convergent top surfaces leading into said slot, 65 a longitudinally disposed yarn passage extending alongside said slot and separated therefrom except at the bottom by a vertically depending elongated partition wall arranged to prevent the lateral escape of yarn from said passage, a yarn-retarding member inserted obliquely through said passage intermediate of its ends. 70 5. A thread block for insertion into a receiving recess in the forepart of a shuttle, 75 embracing a conoidal surfaced forwardly extending beak whose approximately straight inner edge extends slightly beyond the medial axis of the shuttle and a rearward portion laterally offset beyond the inner edge of the beak, said offset portion extending approximately half the length of the block and being vertically slotted throughout its length and having downwardly sloped convergent top surfaces leading into said slot, a longitudinally disposed yarn passage extending alongside said slot and separated therefrom except at the bottom by a vertically depending elongated partition wall arranged to prevent the lateral escape of yarn from said passage, means inserted in said passage intermediate of its ends to restrict the ballooning and frictionally retard the yarn traveling toward the shuttle outlet, while leaving the space below said partition clear for the ingress of the yarn. 80 6. A threading block for insertion in the forepart of a loom shuttle, embracing in its construction a tapered forward portion terminating at its apex in a downwardly extending tip in close proximity to the opposing interior wall of the shuttle forepart, and a rear portion formed with downwardly sloped convergent faces forming an elongated deflecting trough beyond the medial axis of the shuttle, said trough being continued downwardly by an elongated vertical slot, the rear part being also provided with a circularly bored longitudinal passage extending parallel to said slot and having lateral communication therewith at its bottom only by means of an elongated slit, thereby presenting no obstacle to the ingress of yarn into said passage while preventing its lateral escape therefrom. 100 7. A threading block for insertion into the forepart of a loom shuttle having extending longitudinally through its rear portion side by side a cylindrical thread passage, and a narrow vertical inlet slot separated therefrom by an elongated partition wall extending nearly to the common level of the bottoms thereof, and having a forwardly extending tapered beak provided with a depending rearwardly inclined underneath deflecting horn for guiding the inthreaded yarn to the thread-eye of the shuttle. 105 110 115 120 125 In witness whereof, I have subscribed the above specification.
